THERMOSTATIC HEAT CONTROL FOR INTERNAL COMBUSTION ENGINES

Filed Nov. 18, 1920.

Patented Jan. 4, 1927.

1,613,006

UNITED STATES PATENT OFFICE.

REA P. WRIGHT, OF WASHINGTON, DISTRICT OF COLUMBIA, ASSIGNOR TO MARVEL CARBURETOR COMPANY, OF FLINT, MICHIGAN, A CORPORATION OF INDIANA.

THERMOSTATIC HEAT CONTROL FOR INTERNAL-COMBUSTION ENGINES.

Application filed November 18, 1920. Serial No. 424,908.

This invention relates to certain new and useful improvements in thermostatic heat control for internal combustion engines and is a companion application of my applications executed even date herewith, Serial 5 Numbers 424,907 and 424,909, filed November 18, 1920, the object being to provide a thermostatic heat control in which the thermostat is disposed in the path of travel of the 10 explosive charge in its passage to the engine so that the temperature of the charge itself will control the application of heat.

Other and further objects and advantages 15 of the invention will be hereinafter set forth and the novel features thereof defined by the appended claim.

In the drawings.

Figure 1 is a side elevation of an internal combustion engine showing the application 20 of my improved construction of thermostatic heat control thereto, partly in section.

Figure 2 is a section taken on line 2—2 of Figure 1; and

Figure 3 is a detail view of a thermostat.

In the drawings, 1 indicates an internal combustion engine, 2 the exhaust manifold and 3 the intake manifold which is herein provided with a central induction pipe 4 having a bracket 5 on which is pivotally 25 mounted a rocker arm 6. The wall of the induction pipe 4 is provided with a stuffing box 7 in which is slidably mounted a rod 8 having an outer end provided with a pin 9 working in the rocker arm 6 as clearly 30 shown, the inner end of said rocker extending through a slot 10 formed in the free end of a bowed like thermostatic member 11 which is secured to the inner wall of the induction 35 pipe as shown. The rod 8 is threaded and 40 carries nuts 12 to each side of the thermostatic member whereby when the thermostatic member expands the rod will be forced outwardly through the stuffing box and rock the rocker arm 6 as will be hereinafter fully 45 described.

A casting 13 is disposed under the induction pipe having a central carbureting passage 14 which communicates with the outlet of a charge forming device 15, said carbureting 50 passage being surrounded by a heating chamber 16 having an inlet nipple 17 which is connected to an outlet nipple 18 of a coupling 19 by a pipe 20, said coupling being connected to the exhaust manifold 2 and having its other end connected to the

exhaust line pipe 21 which extends to the muffler in the usual manner.

The heat chamber 16 is provided with an outlet nipple 22 having a pipe 23 arranged therein and extending back into the exhaust 60 line pipe or preferably to the atmosphere. Extending transversely through the pipe 23 is a valve stem 24 carrying a valve 25. The valve stem is provided with an arm 26 having a series of openings 27 in which the 65 hooked end 28 of a link 29 is adapted to be adjustably mounted, the other end of the link 29 being pivotally connected to the end of rocker arm 6. By this construction as the thermostat expands and forces the rod 8 70 outwardly the rocker arm 6 is moved so as to operate the valve 25 to close the outlet pipe 23 in order to prevent the exhaust gases from circulating through the heating chamber 16. 75

By connecting the heating chamber to the exhaust line pipe at a point between the engine and muffler when the valve 25 is in open position, the exhaust gases seek the path of 80 travel of the least resistance and pass through the heating chamber. As a certain amount of back pressure is created by the muffler and as the gases circulate through the heating chamber the carbureting passage is heated so that the explosive charge 85 in its path of travel to the engine is heated. The thermostat being arranged in the path of travel of the heated charge acts to control the application of heat so that the charge can be maintained at the proper temperature and 90 by adjusting the link in the arm 26 the position of the valve and the time of closing can be regulated.

When in the position shown, the gases naturally travel through the heating chamber 95 and as the heat of the charge is increased the thermostat expands and gradually closes the valve and when the valve is in closed position, the exhaust gases pass through the ordinary exhaust line pipe and prevent the 100 overheating of the charge.

The construction shown provides a simple means for automatically regulating the temperature of the explosive charge passing to the internal combustion engine but it is of 105 course understood that various changes can be made without departing from the spirit of my invention as I am aware that the heat can be applied to the manifold or to the charge forming device but my invention con- 110

sists broadly in applying heat to the explosive charge in its path of travel to the internal combustion engine and arranging in the path of travel of said charge a thermostat which controls the passage of heating medium to the heater and I reserve the right to apply the heater at any desired point.

What I claim is:—

An internal combustion engine having an 10 exhaust pipe, intake manifold and charge forming device connected thereto, a heater arranged to heat the charge in its passage to the internal combustion engine, said heater being in communication with the exhaust 15 pipe through an unclosable passage and pro-

vided with a valve controlled outlet, said intake manifold being provided with a stuffing box having a rod slidably mounted therein provided with a threaded end, a rocker arm slidably connected to the outer end of said 20 rod and an adjustable connection between said rocker arm and said valve and a bowed thermostatic member mounted within said intake manifold in the path of travel of the charge having a slotted end to receive said 25 rod, said rod being provided with nuts to each side of said thermostatic member.

In testimony whereof I have hereunto affixed my signature.

REA P. WRIGHT.
